UNITED STATES PATENT OFFICE.

WILLIAM PRESTON STUNZ, OF LANSDOWNE, MARYLAND, ASSIGNOR, BY MESNE ASSIGNMENTS, TO THE WEBB TALKING PICTURES COMPANY, A CORPORATION OF DELAWARE.

TRANSMITTER FOR TELEPHONE AND OTHER SOUND-TRANSMITTING INSTRUMENTS.

1,144,391.

Specification of Letters Patent. Patented June 29, 1915.

Application filed December 31, 1910. Serial No. 600,356.

To all whom it may concern:

Be it known that I, WILLIAM PRESTON STUNZ, a citizen of the United States, residing at Lansdowne, in the county of Baltimore and State of Maryland, have invented certain new and useful Improvements in Transmitters for Telephone and other Sound-Transmitting Instruments; and I do declare the following to be a full, clear, and 10 exact description of the invention, such as will enable others skilled in the art to which it appertains to make and use the same, reference being had to the accompanying drawings, and to the letters and figures of reference marked thereon, which form a part 15 of this specification.

My invention relates to transmitters for telephone and other sound transmitting instruments; and it has primarily for its object to produce a transmitter in which the wave vibrations will be received and transmitted with exceptionally well-defined sharpness, clearness and distinctness, and in which also will be obviated the necessity of 20 dampers for the diaphragm of the instrument, and in which also will be embodied structural features calculated to simplify and otherwise improve the construction with the view of producing a transmitter possessing 25 all of the desirable features while at the same time free from the presence of undesirable features and possessing the highest efficiency in the transmission of voice or other wave vibrations.

To the accomplishment of the foregoing and such other objects as may be made hereinafter to appear, the invention consists in the features hereinafter particularly described and then sought to be clearly defined 30 by the claims, reference being had to the accompanying drawings illustrating the preferred form of embodiment of the invention, and in which:

Figure 1 is a front view of the transmitter 45 with the mouth-piece omitted; Fig. 2 a rear end view of the instrument; Fig. 3 a plan view of the instrument; Fig. 4 a central cross-section through the instrument with the mouth-piece omitted, on an enlarged scale; Fig. 5 a detail view of a portion of the casing of the instrument, on an enlarged scale; Fig. 6 a rear end view of the instrument, with the covering plates re- 50 moved; Fig. 7 a rear face view of the diaphragm, showing also the clips or plates and conductors by which the diaphragm rods are connected to binding posts; Fig. 8 is a section through the diaphragm, showing also its rods, the insulating covering of one of the rods being in section, the view being on an enlarged scale; Fig. 9 is a diagrammatic view of the diaphragm and electrodes, showing the preferred manner of connecting the electrodes in circuit; Fig. 10 is a diagrammatic view of the circuit of Fig. 9; Fig. 11 is a diagrammatic view of the diaphragm and electrodes illustrating a modified form of circuit; and Fig. 12 is a diagrammatic view of the circuit embodied in the construction illustrated in Fig. 11. 70

In the drawings the numeral 1 indicates the face-casing of the instrument formed with a threaded portion 2 to receive the mouth-piece 3 and with an internally threaded and chambered portion 4 to receive the diaphragm 5 which will rest upon a shoulder or seat 6 formed for it in the chamber 4, and will be held therein by a disk 7 having threaded engagement with the walls of the chamber 4 and which may be held against movement by screws 8 as illustrated clearly in Fig. 4 of the drawing. Upon the disk 7 is mounted a block 9 made preferably of hard rubber and formed with chambers 10 and 11 to receive granular carbon. The block 9 is recessed next to the disk 7 so as to receive two carbon electrodes 12, 12^a, one for each granular carbon chamber, said electrodes being separated from the disk 7 by a strip 15 of suitable insulating material which also extends between the disk and the block 9. The outer face of the block 9 is recessed so as to receive two carbon electrodes 14, 14^a, one for each of the granular carbon chambers, and within the granular carbon chambers are movable carbon electrodes 13, 13^a, one for each chamber, and which are connected by rods 16, 16^a, to the diaphragm 5, these rods passing through appropriate openings made in the electrodes 12, 12^a and the disk 7 for the purpose of being secured to the electrodes 13, 13^a respectively by nuts 17, 17^a and to the diaphragm by nuts 18, 18^a, insulated from the diaphragm by insulations 19, 19^a, and the rods 16, 16^a may have an insulating covering 75 80 85 90 95 100 105

20, 20^a respectively. The electrodes 14, 14^a are held in place by plates 21, 21^a through which and the block 9 and into the disk 7 pass screws 22 for securing said several parts together. This forms a very simple construction by which the several parts may be readily assembled and also disassociated when desirable.

10 The outer edge of the diaphragm 5 is in- closed by a resilient cushion 23 which may be and preferably is made of rubber, although it may be made of other suitable elastic material; and strips 24, 24^a, of suitable insulating material, are interposed be- 15 tween the cushion 23 and the face-casing 1 and disk 7 respectively. By connecting the diaphragm 5 to the movable electrodes 13, 13^a by the rods 16, 16^a both of said electrodes are caused to move with the diaphragm 5; 20 and by having the outer edge of the dia- phragm 5 inclosed in a resilient cushion 23 interposed between the disk 7 and face-cas- ing 1, the whole diaphragm will move back and forth under the influence of wave vibra- 25 tions and this back and forth movement will be simultaneously imparted to the two move- able electrodes 13, 13^a, so that the granular carbon between those electrodes and the elec- 30 trodes 14, 14^a will be compressed in the movement of the electrodes 13, 13^a toward the electrodes 14, 14^a and simultaneously pressure on the carbon granules between the electrodes 13—12 and the electrodes 13^a— 12^a will be proportionately released while 35 in the opposite movement of the electrodes 13, 13^a the granular carbon between them and the electrodes 12, 12^a will be compressed and the pressure on the granular carbon be- 40 tween the electrodes 13—13^a and the elec- trodes 14, 14^a will be simultaneously and proportionately released.

Since the diaphragm 5 is arranged and supported to move back and forth under vibrations without flexure it follows that 45 the electrodes connected thereto will move back and forth therewith to an equal extent one with the other and consequently the action on the granular carbon in both chambers is the same as to compressing the 50 granules on one side of the two movable electrodes and releasing the pressure proportionately on the granules on the opposite sides of said electrodes in movement of the electrodes and the diaphragm back and 55 forth. In order that the diaphragm may possess the minimum of weight or lightness and at the same time have sufficient rigidity or stiffness to avoid flexure it is made preferably of aluminum and the necessary stiff- 60 ness is given to it by forming it with corrugations, flutes or ribs 29. By connecting each electrode with the diaphragm so that the to and fro movements of the diaphragm will be exerted on the several electrodes in 65 the direction of line of movement of the

electrodes, each electrode is given the same extent of movement and without torsional strain on the several electrodes, and this makes possible the production of the two independent balanced circuits so as to fully 70 utilize the entire product of a simultaneous unbalancing in each granular carbon chamber.

In the preferred form of the invention, as illustrated in Fig 9 of the drawing, the 75 rod 16 is connected by conductor 25 and a clip 26 to a binding post 27 designed to receive the wire which leads to a receiver, and the rod 16^a is connected by a conductor 25^a and clip 26^a to a binding post 80 27^a from which will run the other conductor leading to the receiver. The electrode 14 will be connected by a conductor 28, to a binding post 27^b from which a wire will lead to the source of electrical energy, say, for 85 instance with one pole of a battery and the electrode 14^a will be connected by a conductor 28^a to a binding post 27^a from which a wire will lead to the source of electrical energy, for instance to the other pole of the 90 battery. In this form of the invention the electrode 14 will be connected by a wire or conductor 30 to the electrode 12^a, and the electrode 12 will be connected by a wire or conductor 30^a with the electrode 14^a so that 95 the circuit will include the Wheatstone bridge principle. Under this construction when the diaphragm 5 is moved inwardly and the electrodes 13, 13^a moved toward the electrodes 14, 14^a the granular carbon between said electrodes is compressed so as to 100 create a low potential at the junction point of the Wheatstone bridge and the current will flow from the source of electrical energy, for instance, from one pole of the battery through the conductor 28^a to the rod 16^a thence through the conductor 25^a to the receiver and return by way of the other conductor 25 of the receiver to the rod 16 and thence by way of the conductor 28 to the 105 source of energy or the other pole of the battery, thus completing the circuit. Upon movement of the diaphragm in the opposite direction the granular carbon between the electrodes 13—14 and the electrodes 13^a— 110 14^a will be loosened and the granular carbon between the electrodes 12—13 and 12^a—13^a will be compressed so that the current will flow from the source of energy or battery in the opposite direction to that previously de- 115 scribed and consequently through the now low resistance transmitters formed by the electrodes 12—13 and 12^a—13^a and the compressed granular carbon between them, which transmitters were high when the transmitters formed by the electrodes 13—14 and 13^a—14^a were low when the carbon granules between them were compressed but 120 which are rendered high by compression of the carbon granules between the electrodes 115 125 130

13—12 and 13^a—12^a. In the way specified an alternating current is produced with pressure and volume corresponding to the differences in potential set up at points of 5 normally equal potential proportional to the disturbance created in the transmitter on opposite sides of the normally equal potential points.

The circuit just described is illustrated 10 diagrammatically in Fig. 10 of the drawing. In this form of the invention the current passes in reverse direction through the two transmitters, and when the electrodes 13—13^a are at rest they are in their neutral or 15 no-voltage position and at such time the potentials of the several electrodes are alike, but when the electrodes 13—13^a are moved in one direction or the other differences in potential are set up by reason of the changes 20 in resistance of the granular carbon in the chambers and thus an alternating current is created.

In Figs. 11 and 12 of the drawing there is 25 illustrated a different circuit from that illustrated in Figs. 9 and 10 of the drawing, due to the employment of condensers in the circuit and the manner of connecting the electrodes as illustrated in Fig. 11. In this form the same designating characters are employed 30 for the parts which correspond to like parts in Fig. 9, and additional designating characters employed for the other parts. In the form illustrated in Figs. 11 and 12 the electrodes of one transmitter chamber 35 are connected straight or in multiple with the electrodes of the other transmitter chamber, that is to say the electrode 12 is connected by the conductor 31 with the electrode 12^a; the electrode 14 is connected by 40 the conductor 31^a with the electrode 14^a; and the electrode 13 is connected with the electrode 13^a by the conductor 32 joining the rod 16 of the electrode 13 with the rod 16^a of the electrode 13^a. A wire or conductor 28 45 leads from the conductor 14 to the battery or other source of energy the same as described for the Wheatstone form of the invention illustrated in Fig. 9, and in the wire or conductor 28^a which leads from the electrode 12^a to the battery or source of electrical energy there is included the condensers 33 as 50 illustrated in Fig. 12 of the drawing. In this form of the invention the current flows in the same direction in each transmitter chamber and causes both transmitter chambers to work as one, and when the electrodes 55 13 and 13^a are at rest they are in a no-voltage or neutral position as they are both connected together, and when in operation the alternating or voice current terminals are in 60 the path of the conductor leading from the electrodes 13—13^a to the receiver and in the path of the current passing through the conductor having the condensers 33. With this 65 description taken in connection with the dia-

grammatic illustration of the circuit given in Fig. 12 of the drawing the circuit will be clear to the skilled in the art.

In both forms of the invention the arrangement of the electrodes in each transmitter chamber in relation to each other and to the diaphragm and the construction of the various parts are the same with the exception of the difference in the manner of connecting electrodes of one of the chambers 70 with the electrodes of the other chamber, and in both forms of the invention the features which are in common to both embody the same novel features and advantages. It will be observed that by forming each transmitter chamber with a movable electrode interposed between two other electrodes with granular carbon between the movable electrodes and the other electrodes of the chambers, and connecting the movable electrodes 75 of the two chambers with the diaphragm, there is formed a transmitter in which the granular carbon is compressed in two chambers at the same time and under the same pressure while the carbon granules on the 80 opposite side of the movable electrodes are simultaneously loosened or relieved of pressure proportionately to the compression of the granules on the other side of the movable electrodes, and that in the reverse movement of the movable electrodes a corresponding action and coöperation and release of pressure ensues, so that alternating high and 85 low potentials are produced in the transmitter. This particular arrangement of electrodes in conjunction with the granular carbon increases the efficiency of the transmitter 90 and produces an exceptionally clear and distinct reproduction of wave vibrations which is particularly well adapted for instruments 95 for production and transmission of voice currents, as well as for transmission of other wave vibrations.

Having described my invention and set forth its merits what I claim is:

1. A telephone instrument comprising a plurality of chambers for granular carbon arranged side by side, front and rear electrodes and a movable centrally disposed electrode in each chamber, granular carbon 100 between the several electrodes in each chamber, a diaphragm common to the several chambers and supported to be bodily movable throughout its whole area, and means for separately connecting the diaphragm to the movable electrode of each chamber to simultaneously compress granular carbon in both chambers on one side of the movable electrodes while releasing compression on the granular carbon on the other side of both 105 of said electrodes, substantially as described.

2. A telephone instrument comprising a casing having a chambered portion formed with a diaphragm-seat, a diaphragm resting upon said seat, a backing-disk fitted over 110

the diaphragm, means securing the backing-disk to its adjustment over the diaphragm, a plurality of chambers mounted upon the backing-disk and having each front and rear electrodes and a centrally disposed movable electrode, granular carbon between the several electrodes, and means extending centrally from the face of each movable electrode directly to the diaphragm and connected therewith at points equidistant from the periphery of the diaphragm to exert pressure from the diaphragm on the several electrodes in the direction of line of movement of the electrodes to simultaneously compress granular carbon in both chambers on one side of the movable electrodes while releasing compression on the other side thereof, substantially as described.

3. A telephone instrument comprising a plurality of chambers for granular carbon arranged side by side, front and rear electrodes and a movable centrally disposed electrode in each chamber, granular carbon between the several electrodes in each chamber, a diaphragm common to the several chambers and supported to be bodily movable throughout its whole area, and means connecting each movable electrode to the diaphragm to one side of its center to positively move the several electrodes to the same extent and simultaneously with each other correspondingly to the movement of the diaphragm to compress the granular carbon in each chamber on one side of the movable electrodes while releasing compression on the granular carbon on the other side of both electrodes, substantially as described.

4. A telephone instrument comprising a granular carbon holding chamber containing a movable electrode, and a diaphragm connected with the electrode, said diaphragm formed of relatively thin material and having ribs radiating from its center to render it non-flexible in response to vibrations, substantially as described.

5. A telephone instrument comprising a plurality of chambers for granular carbon

arranged side by side, front and rear electrodes and a movable centrally disposed electrode in each chamber, granular carbon between the several electrodes in each chamber, a diaphragm common to the several chambers, and means extending centrally from the face of each movable electrode directly to the diaphragm and connected therewith at points equidistant from the periphery of the diaphragm to exert equal pressure from the diaphragm on the several electrodes in the direction of line of movement of the electrodes to simultaneously compress the granular carbon in each chamber on one side of the movable electrodes while releasing compression of the granular carbon on the other side thereof, and appropriate electrical connection to form two independent balanced circuits acting in conjunction to utilize the product of a simultaneous unbalancing in each, and each actuated by the same vibration, substantially as described.

6. A transmitter comprising a casing chambered and formed with a diaphragm seat in the chamber, a diaphragm cushioned upon said seat so as to be movable to and fro thereon, a backing disposed opposite said diaphragm, a granular carbon holding receptacle mounted upon said backing and comprising a plurality of chambers each provided with oppositely disposed electrodes and an interposed movable electrode, and means passing through said backing and connecting the diaphragm and movable electrodes and adapted to move the several electrodes to the same extent and simultaneously with each other to compress the granular carbon on one side of the movable electrodes while releasing compression on the granular carbon on the other side of the several electrodes, substantially as described.

In testimony whereof I affix my signature in presence of two witnesses.

WILLIAM PRESTON STUNZ.
